UNITED STATES PATENT OFFICE.

THEODORE HAWLEY, OF NEW HAVEN, CONNECTICUT.

WATER-PROOF WEARING-APPAREL.

SPECIFICATION forming part of Letters Patent No. 236,807, dated January 18, 1881.

Application filed May 17, 1880. (No model.)

To all whom it may concern:

Be it known that I, THEODORE HAWLEY, of New Haven, in the county of New Haven and State of Connecticut, have invented certain new and useful Improvements in Water-Proof Wearing-Apparel; and I do hereby declare that the following is a full, clear, and exact description of the invention, which will enable others skilled in the art to which it applies to make and use the same, reference being had to the accompanying drawings, which form a part of this specification, and in which—

Figure 1 is a rear elevation of my improved water-proof coat, with the sleeves extended and portions in section, showing the air inlets or ducts; and Fig. 2 is a front elevation thereof.

This invention contemplates improvements in water-proof wearing-apparel, specially coats, having for its object their ventilation, to avoid the sweating of the wearer, and otherwise promote comfort; and it consists in the improvements hereinafter described, and particularly pointed out in the claims.

In the drawings, A marks the body of the coat, of any suitable water-proof material and suitably lined. In the upper part of the body or water-proof portion of the coat is an opening, B, extending continuously across the coat, in the back, from each side of the front opening of the coat, with the lower edge of the cape-shaped portion, C, thus formed lapping the upper edge of the opening B, to perfectly exclude the rain, or water, or snow beating against it, while the cape is connected or held to the coat below said edge of said opening by straps or loops a, with one end fastened in under and to the cape, and the other ends slipped or put over buttons b on the coat, and concealed or hid from view by the lapping portion of the cape. A supplemental lining, D, has its lower edge fastened or sewed about at the lower edge of the opening B, with its other edge sewed to the lower edge of the collar, to provide an air-space between it and the cape C.

Upon the shoulders, just at the sleeve-sockets, are additional openings, E, with lapping portions F, for excluding the driving rain, &c., which, with the opening B, fur-

nish inlets for air into the air-space between the supplemental lining and cape C, and thus keep that portion of the body of the wearer (the shoulders) which the coat fits tightly cool, to prevent sweating, which would otherwise occur, and thereby add to the comfort of the wearer.

F F are the sleeves, with their upper ends connected, by some porous or textile material, F', to the supplemental lining D, while covering the porous portions F' of the sleeves are separate continuations F² of the sleeves, which overlap and are buttoned or strapped to the sleeves proper. This arrangement is to ventilate and cool the arms at the body, where, without this provision, they are liable to become overheated and perspire.

The pockets, of which one is represented at G in Fig. 2, have a slit-opening, g, which is provided with corded gores g', that may be either separately covered with rubber and fastened to the coat, or the cord may be inserted under and sewed up in the rubber fabric. The bottom of the pocket proper is connected, by a piece of elastic fabric, h, with the coat fabric, on the inside, in such manner that the fabric h will draw the pocket close up against the side of the coat when it (the pocket) is empty, while the corded gores will prevent water entering from the outside.

The tail end of the coat is provided with a V-shaped gore, instead of being left open.

The lapel of one side of the coat is formed with an extension, H, which is capable of being turned down upon the coat with the turning down of the lapel, when out of use, and is provided with rubber or rubber-covered loops i, embedded in each upper corner thereof, and are adapted to fit over buttons j on each side of the collar, so as to perfectly exclude the water, or rain, or snow from the throat.

The lower ends of the sleeves F are provided upon the inside with supplemental cuffs I, with buttons and holes to adapt them to be buttoned snugly around and to fit them to different-sized wrists, to enable them to prevent the entrance of water at those points, while the other cuffs, I', of the sleeves turn off the water.

One or both the front edges of the coat are corded, as shown at m, and on one side are

the buttons *b'*, while on the other side are coinciding rubber-coated loops *k*, thus avoiding the cutting of button-holes through, and thereby weakening the fabric. If desired, 5 the loops and buttons may be covered by a flap reaching from top to bottom and secured on one of the corded front sides of the coat. I claim as my improvement and desire to secure by Letters Patent of the United States— 10 1. The water-proof ventilative overcoat composed of the skirt *A*, with its porous supplemental lining or extension *D*, cape *C*, extending down over said lining, sleeves *F*, con-

nected by porous fabric *F'* to the supplemental lining or porous extension *D*, and overlapping 15 shoulder-pieces *F²*, as set forth.

2. The V-shaped gore, in combination with the tail end of the coat, substantially as and for the purpose specified.

In testimony that I claim the foregoing as 20 my own I have hereto affixed my signature in presence of two witnesses.

THEODORE HAWLEY.
